UNITED STATES PATENT OFFICE.

CHARLES M. HAYNES, OF NEWARK, NEW JERSEY.

WAGON.

1,161,049.

Specification of Letters Patent. Patented Nov. 23, 1915.

Original application filed December 13, 1912, Serial No. 736,580. Divided and this application filed July 29, 1914. Serial No. 853,811.

To all whom it may concern:

Be it known that I, CHARLES M. HAYNES, a citizen of the United States, residing at Newark, in the county of Essex and State of New Jersey, have invented certain new and useful Improvements in Wagons, of which the following is a specification.

This invention relates to wagons, and while a wagon involving my invention can be employed with advantage in a variety of ways, it is especially intended for the use of children.

Among the objects of the invention are the provision of an article of the character mentioned which is strong in construction and capable thereby of effectually resisting the rough usage of young persons, while at the same time it is comparatively light, so that it can be easily drawn from place to place. The wagon can also be inexpensively made, and its parts readily and quickly assembled.

The invention possesses other features of novelty and utility, which with the foregoing will be stated at length in the following description, wherein I will set forth in detail one of the many forms of embodiment of the invention which I have selected for illustration in the drawings accompanying and forming part of the present specification, so that those skilled in the art can practice the invention. I can depart in several respects from such showing within the scope of the invention defined by the claims following said description.

Referring to said drawings: Figure 1 is a side elevation of a wagon involving my invention. Fig. 2 is a top plan view of the same, with the body removed and with a part in section. Fig. 3 is a top plan view of the central portion of the front axle, the forward part of the reach, a bolster and certain other parts hereinafter described. Fig. 4 is a cross sectional view of said bolster on the line 4—4 of Fig. 3. Fig. 5 is a view as seen from the front of the central portion of the front axle looking in the direction of the arrow in Fig. 6. Fig. 6 is a sectional elevation of said front axle and forward portion of the reach in assembled relation. Fig. 7 is a similar view showing the two parts separated. Fig. 8 is a sectional elevation of the rear axle, a portion of the reach and a brace.

Fig. 9 is a sectional view on the line 9—9 of Fig. 8.

Like characters refer to like parts throughout the several views, which it will be observed are on different scales.

It will also be noted that Figs. 3 to 9 inclusive are details.

The wagon includes in its make-up front and rear axles, and although these may be of any suitable character, I prefer that they be of metal, thus insuring strength without unnecessary weight. The axles shown are preferably angular in cross section for a reason that will hereinafter appear. By this I do not mean to say that I restrict myself to the use of "angle irons," as they are ordinarily known, in the formation of said axles, as in one form thereof the cross section is of T-shape, this in fact being the preferred form, as it is stronger, while in the other the axles are of L-form in cross section and are strictly speaking angle irons. The axles are designated by 2 and 3 respectively and the wheels by 4.

The wheels 4 turn on the spindles 7 connected in some suitable manner with and projecting from the axles, each wheel comprising a web 10 and a rim or felly 11. The rims 11 are interiorly channelled or grooved as at 12 to receive the webs 10. It is conceivable that the rims can be made of channel irons. In fact the type of wheel shown in Fig. 6 is made from this kind of stock. Originally the web 10 is of concave-convex form in cross section, the diameter thereof when the web is in this condition being less than the internal diameter of the rim or felly 11, so that the web 10 can be expansively held in the rim for instance by being inserted thereinto until its periphery is opposite the annular or continuous inner groove 12 at which time the web 10 is straightened by swaging or some other operation, so as to project the marginal or rim portion of the web fully into the groove 12 and thereby firmly unite the web and rim of the wheel.

The spindle 7 extends through the sleeve 13, the tapered portion of which projects through a central opening in the web or disk 10 and into the cap 14 provided with a circular flange 15 equipped with inwardly extending studs or projections 16 projecting

through slots in the web 10 and through perforations in a flange of said sleeve 13 and headed. The sleeve 13 and cap 14 are therefore rigidly connected with each other and with the web 10. The transverse wall of the cap 14 is perforated for the passage of said spindle 7, the head of said spindle bearing against the outer face of said wall. Within the cap 14 is a space or chamber 10 and in the same can be put some lubricant absorbing substance or packing to be saturated with a lubricant to lubricate the axle 7 through an oil hole in the cap.

The reach is denoted by 24, and may be 15 made in the form of a T in cross section or of L-form in cross section. As illustrated, however, it is of T form. The rear end portion of the web of the reach 24 is cut away or reduced to produce the stud or 20 projection 25 which is passed through a perforation in the pendent web of the rear axle 2 after which it is headed as at 26 which under ordinary circumstances is a sufficient and proper connection between 25 said reach and rear axle, although as a matter of extra strength I prefer to extend braces as 27 between the said rear axle and said reach, the terminal portions of the angularly disposed braces being bent to fit 30 against the webs of said axle and reach and to be connected firmly therewith in any suitable manner as by rivets 28.

The reach 24 is cut away at its forward end on the upper side thereof to produce 35 the extension 29, said extension 29 being slotted to form the hook 30, the web of the T-shaped front axle having at or near its center, the T-shaped slot 31 for the passage of the hook 30. In connecting the reach 40 24 with the front axle, the web of the reach is positioned at right angles to that of the front axle as shown in Fig. 12, so that the hook 30 can pass through the transverse portion of the T-slot 31 after which the two 45 webs are turned relatively at right angles, so that the hook 30 can be interlocked with the web of the front axle to thus prevent separation of the same and to also pivotally connect the reach and front axle to insure 50 proper turning of the latter without the necessity of using a king bolt. The slot 31 is preferably of T-form, although it need not always be made in this particular form. An advantage, however, follows this particular 55 point in that the shank of the hook 30 can be made comparatively deep which would not be the case were said slot straight, which, however, is a possible and conceivable construction. The shank of the hook 30 fits partly 60 in the vertical portion of the T-slot 31 with the bill of said hook opposite the front side of the web of the forward axle. The vertical portion of the T-slot retains the inserted end of reach at the middle point of 65 the axle.

The fifth wheel 32 is of half circular form and between its ends extends through a longitudinal slot 33 in the web of the reach 24, its terminals being reduced, extending through perforations in the web of the front axle and headed as at 32' on the front side of said axle to thus hold said fifth wheel in place. The fifth wheel or bowed member 32 does not affect free tipping movement of the forward axle to which the same would naturally be subjected, owing to the unevenness of a road. It does, however, effectually prevent abnormal movement of said axle to an extent sufficient to prevent the reach being disengaged therefrom.

The body of the wagon is denoted by 34, and it may be fastened by bolting or riveting to the rear axle 2 and in like manner to the bolster 35 which has a T-slot or opening to receive the similarly shaped reach 24. The bolster is therefore slidable on the reach, making it adjustable to different sized bodies, the body of whatever character it may be, holding said bolster in adjusted position when fastened thereto.

The present case is a division of my co-pending application No. 736,580 filed December 13, 1912, wherein I cover the axle.

What I claim is:

1. A wagon comprising an axle, and a reach, the axle being of angular form in cross section and the web having a slot, the reach having a hook extending through said slot and engaged over the web of the axle. 100
2. A wagon comprising a front axle and a reach, the axle being of angular form in cross section and the web thereof having a slot, the reach being reduced at its forward end and cut away to present a hook, the hook extending through said slot and overhanging the web to pivotally and interlockably connect the reach and axle. 105
3. A wagon comprising a front axle, a reach having a pivotal hook connection 110 with the front axle, and a bowed member connected at its ends with the axle, the reach having a slot for the free passage of said bowed member, said bowed member acting to prevent accidental separation of the reach from said axle. 115
4. A wagon comprising an axle and a reach, the body of the axle having a slot, the reach having a hook extending through said slot and engaged over the body of the 120 axle.
5. A wagon comprising an axle and a reach, the body of the axle having a slot, the reach having a hook extending through said slot and engaged over the body of the 125 axle, and means for positively preventing the reach from becoming accidentally unhooked from the axle.
6. A wagon comprising a front axle and a reach, the axle having a slot in the body 130

between the ends thereof, the reach being reduced at its forward end and cut away to present a hook, the hook extending through said slot and overhanging the body 5 to pivotally and interlockably connect the reach and the axle.

7. A wagon comprising a front axle, a reach having a pivotal hook connection with said axle, and a bowed member fixed at its 10 ends to the axle and slidably connected be-

tween its ends to the reach, said bowed member acting to prevent accidental separation of the reach from the axle.

In testimony whereof I affix my signature in presence of witnesses.

CHARLES M. HAYNES.
